US0D1111983S

(12) **United States Design Patent** (10) Patent No.: **US D1,111,983 S**
(45) Date of Patent: ** Feb. 10, 2026

(54) **STEP FOR VEHICLE**

(71) Applicant: **Volvo Truck Corporation**, Gothenburg (SE)

(72) Inventors: **Lukas Yates**, Kernersville, NC (US); **Luis Jimenez Carrillo**, Winston-Salem, NC (US)

(73) Assignee: **Volvo Truck Corporation**, Gothenburg (SE)

(**) Term: **15 Years**

(21) Appl. No.: **29/964,856**

(22) Filed: **Sep. 25, 2024**

(51) **LOC (15) Cl.** **12-16**

(52) **U.S. Cl.**

USPC **D12/203**

(58) **Field of Classification Search**

USPC D12/203, 196, 190, 93; D25/69
CPC .. B60R 3/00; B60R 3/02; B60R 3/002; B60R 3/005; B60R 3/007
